INVENTOR
HANS ERNST.

BY *Adam E. Fisher*
ATTORNEY

UNITED STATES PATENT OFFICE.

HANS ERNST, OF ALTON, ILLINOIS.

INTEGRAL NON-METALLIC CARTRIDGE-CASE.

1,364,871.

Specification of Letters Patent. Patented Jan. 11, 1921.

Application filed March 7, 1919. Serial No. 281,239.

To all whom it may concern:

Be it known that I, HANS ERNST, a subject of the King of Great Britain, residing in the city of Alton and State of Illinois, have invented new and useful Improvements 5 in Integral Non-Metallic Cartridge-Cases, of which the following is a specification, reference being had to the accompanying drawings.

10 This invention pertains to shot or cartridge cases, as ordinarily used in shot-guns or other guns of small caliber, and has for its object the provision of a non-metallic one-piece cartridge case constructed or 15 molded of papier mâché, vulcanite, red fiber or any other similar non-metallic composition.

Another object is to so construct such cases 20 that there will be a gradual tapering of the bore of the case from the front to the base, whereby the base of the case and the wall immediately adjoining will be thicker than the balance of the case wall, thereby offering greater and sufficient resistance to the 25 explosive force of the charge contained in the case.

Another object is, by the said one-piece construction of said case, to produce a case 30 which will be cheap or economical in the manufacture and yet efficient in use.

With these objects in view, attention is called to the accompanying drawing wherein:—

Figure 1 is a longitudinal cross-section of 35 my improved case;

Fig. 2 is a front end view;

Fig. 3 is a cross-section taken on the line A—B in Fig. 1;

Fig. 4 is a rear end view;

40 Fig. 5 is a detail showing the method of drawing or burring the rear face of the base of the case over the battery cup in order to hold the battery cup in permanent position.

Fig. 6 is a modification showing a slight 45 metal reinforcement around the base.

Fig. 7 is a sectional view illustrating the manner of molding the cartridge case.

Referring more particularly to the drawings, my invention consists in forming, 50 pressing or molding the composition material, such as papier mâché, vulcanite or the like non-metallic material into the form substantially represented in Fig. 1, so that the case body 1 will have a relatively thin front- 55 tal wall 2 and a relatively thick rear wall 3

formed by the tapering of the bore 4 of the case from the forward to the rear end. In this construction a relatively thick base portion 5 is left, the same being formed integral with the case body 1. This base portion 5 60 represents and takes the place of the ordinary bases. This base portion 5 is formed with a port 6 to receive and frictionally engage the battery cup or primer 7. Into this port 6 the primer 7 is pressed and counter- 65 sunk slightly below the face 8 of the base portion 5 and an annular bur 9 is pressed down upon and around the outer edge of the primer 7, thus locking it firmly in position. The concave inner face of the base merges 70 into the interior taper of the body and forms tapering connecting portions at the juncture of the body and the base. Also the integral bur at the outer end of the primer port by projecting over the outer end of the primer 75 not only urges the primer in the port, but provides a sufficient amount of the non-metallic material at the outer face of the base to protect the primer when the cartridge case is arranged in an upright position upon a 80 supporting surface.

Any slight changes or variations in the construction described may be made without departing from the spirit of my invention as laid down in the appended claim; for instance, the base portion 5 may be reinforced 85 with a metal strip 10 in order to lessen the thickness of said base portion.

What I claim to be new and patentable is:

An integral non-metallic cartridge case 90 consisting of a hollow body formed solely of tough non-metallic material and having an interior taper from front to rear, and a base integral with the body and provided with a concave inner face merging into the interior 95 taper of the body and forming continuous unbroken tapering connecting portions at the juncture of the base and the body, said base having a primer port enlarged at the outer end and provided therewith an integral bur or portion overhanging the enlarged portion of the primer port and arranged to retain a primer in the port and to form a cushion for protecting the outer end of the primer. 100

HANS ERNST.
